UNITED STATES PATENT OFFICE

OLIVER L. CUPP AND JOHN C. ATTERBURY, OF MADISON, MISSOURI

CLAMP OR HOLDER FOR EGG CASE TOPS

Application filed September 18, 1931. Serial No. 563,519.

This invention relates to clamps or holders for efficiently securing lids or tops to cases, crates, boxes, etc., and has for the primary object, the provision of a device of the above stated character which may be easily and quickly applied and removed from a container and its closure without the employment of a special tool and when applied will prevent the closure from bulging throughout its length under the influence of the contents of the container or from becoming accidentally detached therefrom.

Another object of this invention is the provision of means whereby the device may readily adjust itself to a container and permit the application or use thereof on containers which may vary slightly as to size.

With these and other objects in view, this invention consists in certain novel features of construction, combination and arrangement of parts to be hereinafter more fully described and claimed.

For a complete understanding of our invention, reference is to be had to the following description and accompanying drawing, in which

Figure 1 is a top plan view illustrating a clamp or holder applied to a container and its closure and constructed in accordance with our invention.

Figure 2 is a similar view illustrating the clamp or holder, prior to being moved into a securing position.

Figure 3 is a fragmentary side elevation of a container and its closure showing the clamp applied.

Figure 4 is a fragmentary end elevation illustrating the same.

Figure 5 is a perspective view illustrating the tensioning element of the clamp or holder.

Referring in detail to the drawing, the numeral 1 indicates a container provided with end flanges 2 and a closure 3 resting upon the upper edges of the container and to efficiently secure the closure to the container, our in-

vention is provided and comprises a pair of looped elements 4 adapted to fit under the flanges 2 and over the closure 3 as shown in Figure 3 and each is provided with spaces eyes or loops 5 located adjacent the ends of the looped elements 4. Substantially V-shaped connecting elements 6 are pivotally connected with the eyes or loops 5 and extend toward each other over the closure 3 and their apexes are provided with eyes 7 to receive looped ends of connecting rods 8. The adjacent ends of the connecting rods 8 are pivotally secured to a tensioning element 9 as shown at 10. The connecting rods 8 are pivoted to the tensioning element 9 at opposite sides of the center and adjacent the edges thereof so that when the tensioning element is rotated in one direction the connecting rods 8 will be drawn toward each other causing the looped elements 4 to tightly bind against the closure 3 and the container 1, thus firmly securing the closure in place and will prevent the closure from bulging throughout its length due to the pressure of the contents of the container thereagainst.

At opposite sides and adjacent the ends of the tensioning element 9 flanges 11 are provided and adapted to engage over the connecting rods 8 as shown in Figure 1 for holding the tensioning member in a position to cause the securing of the closure to the container. When it is desired to remove the device from the closure and container it is only necessary to disengage the flanges 11 from the connecting rods 8 and turn the tensioning element in an opposite direction placing sufficient slack in the device that the looped elements 4 may be easily disconnected from the flanges 2 of the container and the closure 3.

If desired the tensioning element 9 may be provided with an opening adjacent one end to receive a wire seal after being placed in engagement with some other portion of

the device so that the container may be sealed against unauthorized opening.

Each of the looped members 4 is constructed from a single length of material bent upon itself to provide an elongated loop with the spaced eyes 5 and having the ends arranged in overlapped relation and bent to form hook shaped portions 12 slidably engaging each other so that the looped element 4 is capable of having a limited expansion and for facilitating the application and removal thereof to a container and its closure. Due to the V-shaped elements 6 when tension is placed on the looped elements 4 by the tensioning element 9, said looped elements will be slightly contracted, thereby more efficiently securing the looped elements to the container and its closure.

Suitable metallic plates may be connected to the V-shaped elements 6 on which advertisements may be applied.

While we have shown and described the preferred embodiment of our invention, it will be understood that minor changes in construction, combination and arrangement of parts may be made without departing from the spirit and scope of our invention, as claimed.

Having thus described our invention, what we claim is:

1. A clamp comprising looped elements to be positioned in engagement with opposite ends of a container and over the closure thereof, connecting elements secured to the looped elements and extending in the direction of each other over the closure, a tensioning element pivotally connected to the connecting elements and adapted to be rotated in one direction for drawing the looped elements into tight engagement with the container and the closure, and hook shaped elements on the tensioning element adapted to engage the connecting elements for holding the tensioning element against reverse rotation.
2. A clamp comprising adjustable looped elements to be positioned in engagement with the opposite ends of a container and over the closure thereof and provided with spaced eyes, V-shaped elements pivoted to the eyes and overlying the closure connecting elements pivoted to the V-shaped elements, a tensioning element pivoted to the connecting elements with the pivots of said elements arranged at opposite sides of the center of the tensioning element, said tensioning element adapted to be turned into substantial parallelism with the connecting elements for drawing the looped elements tightly against the container and the closure, and hook shaped portions formed on opposite sides of the tensioning element to engage the connecting elements for holding the tensioning element in parallelism with the connecting elements.
3. A clamp comprising looped elements to be positioned in engagement with opposite

ends of a container and over the closure thereof and each constructed from a single length of material bent into looped formation with the ends thereof arranged in overlapped relation and slidably connected, V-shaped connecting elements pivoted to the looped elements adjacent the ends thereof, and means for connecting and tensioning the V-shaped elements to draw the looped elements tightly against the container and the closure.

In testimony whereof we affix our signatures.

OLIVER L. CUPP.
JOHN C. ATTERBURY.
